(57) **CLAIM**

The ornamental design for a vented lid for a container, as shown and described.

DESCRIPTION

FIG. 1 is a front perspective view of a vented lid for a container;

FIG. 2 is a front elevation view of the invention illustrated in FIG. 1;

FIG. 3 is a top plan view of the invention illustrated in FIG. 1;

FIG. 4 is a bottom plan view of the invention illustrated in FIG. 1;

FIG. 5 is a left elevation view of the invention illustrated in FIG. 1; and,

FIG. 6 is a front perspective view of the invention shown in FIG. 1, the broken lines representing environment for illustrative purposes only and forming no part of the claimed design.
